Primary Examiner — Thomas Johannes*Assistant Examiner* — Chelsea Sealey(74) *Attorney, Agent, or Firm* — Knobbe Martens Olson & Bear LLP(57) **CLAIM**

The ornamental design for a closed-backed mobile device case, as shown and described.

DESCRIPTION

FIG. 1 is a front view of a closed-backed mobile device case in the closed position, showing my new design;

FIG. 2 is a rear view thereof;

FIG. 3 is a top view thereof;

FIG. 4 is a bottom view thereof;

FIG. 5 is a left view thereof;

FIG. 6 is a right view thereof;

FIG. 7 is a front view of FIG. 1, with the latch unclasped;

FIG. 8 is a right view of FIG. 7 thereof;

FIG. 9 is an external view of FIG. 7 in the open position; and, FIG. 10 is an internal view of FIG. 7 in the open position.

1 Claim, 10 Drawing Sheets(56)
